UNITED STATES PATENT OFFICE.

HENRY LA VINE, OF ROCHESTER, NEW YORK.

LAMP.

No. 907,613.

Specification of Letters Patent.

Patented Dec. 22, 1908.

Application filed April 3, 1908. Serial No. 424,968.

To all whom it may concern:

Be it known that I, HENRY LA VINE, a citizen of the United States, residing at Rochester, in the county of Monroe and State of New York, have invented new and useful Improvements in Lamps, of which the following is a specification.

This invention relates to lamps, and the object of the invention is to provide a suitable casing or lantern adapted for the reception of the bulb of an ordinary incandescent electric lamp, the socket of the lamp being retained in a suitable split collar provided by the lantern, and the lantern being provided with a suitable reflector for directing the rays of light and also being provided with spaced bars directly opposite the reflector which protect the bulb within the lantern.

Another object of the invention is to provide a portable casing for incandescent electric lights in which an electric lamp bulb may be readily positioned or withdrawn when desired.

With these and other objects in view the invention resides in the novel construction and arrangement of parts, hereinafter fully described and claimed.

In the accompanying drawings, Figure 1 is a side elevation of a device constructed in accordance with the present invention. Fig. 2 is a top plan view of the same. Fig. 3 is a central longitudinal section. Fig. 4 is a horizontal section upon the line 4—4 of Fig. 1.

In the accompanying drawings the numeral 1 designates the casing or lantern. This casing comprises a top portion 2 and a bottom portion 3. The top and bottom are connected near their outer periphery with a plurality of rods 4, upon the front or face of the lantern, and at their rear with a suitable casing 5. The bottom of the casing comprises a solid sheet of material, while the top 2 of the lantern connecting the rods 4 and casing 5 comprises an annular ring 6. Positioned between the ring 6 and the bottom 3 adjacent the casing 5 is a suitable reflector 7. This reflector 7 is preferably composed of a plurality of longitudinal strips of luminous material and these strips may be interposed between the top and bottom of the lantern in guideways 8, as clearly illustrated in Fig. 3 of the drawings.

The lantern 1 is provided with a suitable handle 9, preferably connected to the center of the casing 5, and by which the device may be carried from place to place when desired.

It will be noted by referring to Fig. 3 of the drawings that the base 1 of the lantern is of greater width than the top 2. By this arrangement it will be noted that the lantern is provided with a secure bearing when resting and the liability of its tilting from the weight of the wires connecting with the electric lamp which the lantern is adapted to receive is obviated. The base 3 is also provided with a plurality of legs or supports 10, so that heat from the lamp imparted to the lantern will not affect the article upon which the lantern rests.

The ring 6 is provided with an annular closure 11. This closure 11 is hinged as at 12 and has its diametrically opposite edge provided with a sliding or pivoted latch 13 adapted to engage a keeper 14 provided upon the ring 6. The closure 11 is provided with a central annular aperture and is also provided with an upwardly extending collar having its walls alining with the aperture. The collar 15 is provided with an annular flange or offset by which it is secured upon the closure 11 for approximately half its circumference. The opposite half of the collar 15 remains free, and the ends of the collar are provided with offsets having suitable perforations adapted for the reception of retaining elements, by which the sections of the collar may be forced towards each other.

The metallic portion of the bulb is adapted to be positioned within the collar 13, and the lamp socket screwed to the metallic portion extends upon the outside of the collar as illustrated in the figures of the drawings. The bulb of the lamp is projected within the lantern, and the key by which the light is regulated is on the exterior of the lantern and in ready reach of the operator.

From the above description taken in connection with the accompanying drawings it will be seen that the bulb may, if desired, remain a permanent portion of the lantern and that it may be connected with a removable lamp socket when desired. It will be also seen that the bulb within the lantern is thoroughly protected from contact with obstacles and that the lantern provides a suitable reflector whereby the rays from the lamp may be concentrated upon any desired object. It will be still further seen that should it be desired the bulb of the lamp may be readily removed from the lantern by releasing the retaining element of the spring collar 15, allowing the lamp to become dis-

connected from the collar, and the door or closure 11 swung open, when the bulb may be readily removed.

Having thus fully described the invention 5 what is claimed as new is:

In a device for the purpose set forth, a lantern having a top ring and a base, bars connecting the ring and the base at the front of the lantern, a casing connecting the top ring 10 and base at the rear of the lantern, a handle upon the casing, a reflector for the lantern, a

closure for the top ring of the lantern having a split collar provided with a retaining element, whereby an electric lamp bulb may be secured within the lantern, and a latch for 15 the closure.

In testimony whereof I affix my signature in presence of two witnesses.

HENRY LA VINE.
